UNITED STATES PATENT OFFICE.

CHARLES B. STEPHENS, OF GRANBY, CONNECTICUT.

CLOCK.

No. 866,533.

Specification of Letters Patent.

Patented Sept. 17, 1907.

Application filed February 21, 1906. Serial No. 302,198.

To all whom it may concern:

Be it known that I, CHARLES B. STEPHENS, a citizen of the United States, residing at Granby, in the county of Hartford and State of Connecticut, have invented 5 a new and useful Clock, of which the following is a specification.

This invention relates to a clock which has a luminous dial.

The object of the invention is to produce a clock 10 with a dial which is simple and inexpensive to manufacture, easy to apply and which has a large surface for receiving and storing rays of light in the daytime and a surface which will reflect the rays emanated at night in such a manner that an efficient glow results in the 15 darkness.

This invention resides in a clock having a hollow dial with a luminous interior surface and having hour indicating characters applied about its periphery in such manner as to exhibit a prominent contrast with 20 the luminous surface and arranged so as to be exposed to the rays emanated from the interior of the dial and at the same time to be easily observed from the front, and having dark prominent pointers that extend from the bottom of the cavity toward the indicating characters about the periphery of the dial.

Figure 1 of the accompanying views shows a front elevation of a clock that embodies the invention. Fig. 2 shows a diametrical section of the dial and the pointers.

30 The case 1 of the clock may be formed of wood, metal or other material, as desired, and may be ornamented as taste dictates. This case, however, must be considerably thicker than cases of the common clocks.

35 The dial 2 which is preferably formed of aluminum is hollow and is located in the case with the cavity opening toward the front. The cavity in the dial may be cylindrical, conical, or semi-spherical, but it is preferably parabolic, as shown in the drawings. The 40 periphery of the dial is circular and the edge is preferably flared outwardly at about an angle of 45° with the plane of the front of the clock case. On the beveled or inclined outer edge of the dial are the time indicating characters. These characters may be Roman or 45 Arabic, as desired, or they may be letters, and they

are preferably white on a square black ground. Through the center of the inner end is a perforation for the minute arbor 3 and the hour sleeve 4. On the arbor is a minute hand 5 and on the sleeve is an hour hand 6. These extend from the center outwardly and 50 are preferably made of black material and rather heavy so as to be conspicuous by contrast with the surface of the dial.

The entire inner surface of the hollow dial and preferably the portion of the rim between the time indicating 55 characters is coated with a common luminous compound, that is, a compound which is hard and which absorbs and stores light rays in the daytime and will throw off light rays in the darkness to such an extent as to produce a glow.

60 When the dial is made with a parabolic inner surface, such as is shown in the drawings, it has a large area for collecting and storing light rays in the daytime and of course it has a correspondingly large surface to glow at night and this surface reflects the rays in such 65 manner as to intensify the glow.

The numbers on the flaring periphery of the dial are exposed to the rays thrown off by the luminous surface and consequently are readily seen and at the same time they are easily observable from the front of the 70 clock so that they may be clearly read in the dark. The pointers are long and heavy and of a contrasting color and are arranged within the parabolic glowing concavity in such way that they offer a striking contrast and consequently are quite visible in the dark. 75

The invention claimed is:—

1. A clock having a case, a dial with a parabolic interior surface coated with luminous compound, said dial having an angularly flaring outer edge, and time indicating characters arranged on the flaring edge, and pointers arranged in the cavity and extending toward the characters, substantially as specified.

2. A clock dial having a parabolic interior surface coated with luminous compound, said dial having an angularly flaring outer edge and time indicating characters arranged on the flaring edge, substantially as specified.

CHARLES B. STEPHENS.
